ATTORNEY.

UNITED STATES PATENT OFFICE.

FREMONT D. PALMER, OF NORWICH, CONNECTICUT, ASSIGNOR OF ONE-HALF TO REUBEN T. PALMER, JR., OF NEW LONDON, CONNECTICUT.

CHILD'S CRIB.

SPECIFICATION forming part of Letters Patent No. 588,001, dated August 10, 1897.

Application filed January 26, 1897. Serial No. 620,803. (No model.)

To all whom it may concern:

Be it known that I, FREMONT D. PALMER, a citizen of the United States, residing at Norwich, in the county of New London and State 5 of Connecticut, have invented certain new and useful Improvements in Children's Cribs, which improvements are fully set forth and described in the following specification, reference being had to the accompanying sheet 10 of drawings.

The object of this invention is to provide a crib of such construction that the same may be folded to reduce its height, thus compacting it and making it possible to stow away 15 the crib in a much smaller space than would be possible otherwise.

To assist in explaining my invention, the accompanying drawings have been provided, serving to illustrate the same, as follows:

20 Figure 1 shows in perspective my newly-invented crib. Fig. 2 shows in elevation and partly in section a portion of one side of said crib and explains the manner in which its folding is accomplished. Fig. 3 shows 25 in elevation and partly in section one end of my crib, illustrating particularly a modification in the construction thereof; and Fig. 4 illustrates still other modifications.

Referring to the drawings, the letters *a* 30 denote the corner-posts of my crib, which, as well as other portions of the crib's framework, are constructed, preferably, of tubing in conformity with the present style of construction of this class of furniture. Corner- 35 posts *a* are supported and tied together by means of horizontal rods *b b'*, thus providing the main framework of the crib, as shown in Fig. 1, which framework serves to support the bed portion thereof. The said main frame- 40 work is rectangular in plan, and located at opposite ends thereof are rectangular frames *c*, constituting the head and foot portions of the crib sides. Frames *c* are hinged to the said frame of the crib, and such hinging is 45 effected by forming eyes *a'* on the upper ends of the corner-posts, which eyes inclose the lower corners of the rectangular frames *c*.

The bed portion of the crib is suspended 50 from the head and foot frames *c* or, prefer- ably, from a cross-rod *c'*, located therein about midway the height of said frames. To thus

suspend the bed portion of the crib horizontal rods *d* are provided at each side of the crib, which rods extend parallel to the crib's length and are approximately of equal length 55 therewith. Rods *d* are located above and rest upon the rods *c'*, and at each end are turned downward, as at *d'*, at right angles to their length, such downwardly-turned portions *d'* being secured to the bed-frame *e*. Netting *f* is shown as stretched for the support of the mattress, but any other suitable means for its support may be as well employed.

The downwardly-extending portions *d'* of the rods *d* are of such length that when frames 65 *c* are rocked to a vertical position the bed-frame *e* is raised to the proper height for the use of the crib, as very clearly shown in Fig. 1, and it will also be understood that when the various elements of my device are in the 70 positions shown in said Fig. 1 the frames *c* form the head and foot portions of the crib, while rods *d* form the side rails thereof, it being of course understood that the skeleton frame thus provided may be more fully filled 75 in without departing in the least from the spirit of my invention. When, however, the crib is not required for use, and it is desired to fold up the same, the frames *c* are rocked downward, (toward the center of the crib,) 80 causing the rods *c'* to slide beneath the rods *d*, which they support, thus lowering the latter and correspondingly lowering the connected bed portion of the crib. This downward rocking of frames *c* is continued until 85 the cross-rod forming the upper side of the frames *c* comes in contact with rods *d*, as shown in Fig. 2, from which figure it will be seen that the bed portion *e* of the crib has been greatly lowered, and also that the up- 90 right frames *c* of Fig. 1 have been rocked downward out of the way and that the crib now occupies much less room than when in the open position of Fig. 1, thus making it possible to stow the same away in a much 95 smaller space than could otherwise be done—as, for example, the crib could be slid under an ordinary bed when not in use.

In order to prevent the accidental folding of the crib, which would result if either or 100 both of frames *c* chanced to be "knocked down," suitable means may be provided for

locking the same in their vertical position. In Figs. 1 and 2 such locking device is provided by bending the portions of rod d engaged by rods c' , as shown in said figures at 5 d^2 , thus providing a recess in which rods c' lie and from which they could not be well displaced by accident. Other means for the locking of frames c will also suggest themselves— 10 as, for example, a hook or catch; but as this particular feature forms only a detail of my invention it is thought unnecessary to describe it further.

In Fig. 3 I have varied the shape of the frames c by doing away with the rod c' of such frames, the said rods d in said figure being shown as supported upon shoulders c^2 , formed on said frame, corresponding in location to the rod c' . A frame thus shaped may be lowered until all weight of the bed is removed 20 therefrom and supported by the upper end rods b of the crib's main frame, as will be understood from reference to Fig. 2, and thus said bed portion would be lowered still more than in Fig. 2.

25 Fig. 4 illustrates two other modifications of my invention, one of which shows the bed-frame e suspended from frames c by means of a link g , said frame being raised and lowered by the rocking of the former, as will be 30 readily understood. The other modification of my invention shown in Fig. 4 consists in providing a telescopic corner-post a , the lower portion a^2 of said post being adapted to slide within the upper tubular portion thereof and 35 having a pin a^3 lying in a slot a^4 in said tubular portion, the lower part of which slot extends at right angles to its length, so that said pin may be turned slightly into said angular slot when it is desired to lock the lower 40 portion a^2 of the post in its extended position. The last-described feature enables the height of the crib to be greatly reduced when the same is folded, but it is not essential to the successful working of my invention.

45 My invention as a whole is not expensive

to produce, is of simple construction, of great convenience, and meets fully the requirements for which it was designed.

Having thus described my invention, I claim—

1. In a crib, the combination, with a framework provided with posts, the upper ends of which are each formed into an eye, a frame hinged within the respective eyes at each end of the crib, a bed-bottom within the framework, and means for supporting said bottom from the frames at the end of the crib, substantially as set forth.

2. In a crib, the combination, with a framework, of a frame pivotally secured at each end thereof, a bed-bottom within the framework, a side rail secured to each side of the bottom, portions of each rail engaging with the frames at the ends of the crib and being supported in an elevated position thereby, substantially as set forth.

3. In a crib, the combination, with a framework, of a frame pivotally secured at each end thereof, a bed-bottom within the framework, each side of which is provided with a side rail above the same, each end of the elevated portion of the rails being provided with a curved portion to engage with the frame and lock the same when in its elevated position, substantially as set forth.

4. In a crib, the combination, with a framework, of a frame pivotally secured at each end thereof, the top of the frame being provided with a bent portion on each side of the crib, a bed-bottom within the framework, each side of which is provided with a side rail above the same, each end of the elevated portion of the side rails engaging with the bent portion of the frames when in an elevated position, substantially as set forth.

FREMONT D. PALMER.
